UNITED STATES PATENT OFFICE.

PAUL HÄNEL, OF DRESDEN, GERMANY, ASSIGNOR TO J. M. LEHMANN, MASCHINEN-FABRIK, A FIRM.

HYDRAULIC POT PRESS.

Application filed October 18, 1924, Serial No. 744,339, and in Germany November 6, 1923.

This invention relates to hydraulic pot presses, which are especially used for removing the oil from cocoa powder, consist, as known, of a column of press pots which are open on two sides and receive a piston. Intermediate pieces (press heads) alternate with said press pots. These intermediate pieces serve on the one hand as a cover for the press pots and on the other hand transmit the pressure of the piston to the next following press pot. For the purpose of charging or discharging the press pots, these have to be loosened from their pressure heads, and removed laterally from the column. For the pressing operation, the press pots must be tightly screwed up against their pressure heads. Until now the screwing up and off was necessary for each pot, which by the numerous press pots and the screw places of each pot, required a great deal of inconvenient and lengthy work by the operatives.

According to the invention, the press pots can be screwed up, and released by handling of a driving gear from a single place. The parts of the driving gear are arranged along the press column so that they can operate, during the time the press is not under pressure, on the means for closing the pots against the intermediate pieces, in such a manner as not to hinder the shortening of the column resulting from the pressing of the column. The means for screwing up the press pots can be of different structures and therefore the driving gear can be of different kinds.

In the following, two forms are described, in one of which screws, and in the other, springs are used for closing the press pots. In the first, the screws screw up or off, and in the other, the springs are made efficacious or ineffectual.

This invention consists in the improvements in hydraulic pot presses, which will be hereinafter more fully described, illustrated in the accompanying drawings and subsequently incorporated in the subjoined claims.

In the drawings wherein I have illustrated several embodiments of my invention and whereby similar reference characters

designate corresponding parts through the several views:—

Figure 1 is a vertical section; and

Figure 2 is a cross section of a vertical press;

Figure 3 shows a vertical section, and

Figure 4 a cross section of a vertical press showing another embodiment of my invention.

Referring to the drawings and more particularly to Figures 1 and 2, the hydraulic piston has fastened thereto the first intermediate piece, or pressure head B.

The press pots are marked with C, C¹ 65 and C², and the other pressure heads with B¹ and B².

D is the cross head or abutment of the press, which at the same time, with regard to the upper pot C², takes the place of an intermediate piece and serves as a cover for this press pot. The press pots may be pushed laterally into the slide blocks c, c¹ and c², which are guided by the bars 1, and by the members 5 of the driving gear. 75

In the flanges of the pressure heads B¹ and B² are rotatably arranged longitudinal bored box-shaped screws 2. These find their female threads in the nuts 3, which are non-rotatably held by the slide blocks. Between the nuts and the base of the bore which contains the nuts, are arranged pressure springs 4. The screws 2¹ in the cross head D act together with their nuts in the slide blocks c² in the same manner as the screws 2. Through the screws, which lie one upon another, extend the shafts 5, guided along the side of the column. These shafts are by means of slot and key rotatably connected with the screws 2, and 2¹ to permit relative axial displacement. The shafts 5 are connected by means of bevel gears 6 with a transverse shaft 7, which is also connected by means of a bevel gear 8, with a vertical driving shaft 9. Shaft 9 is provided with crank wheel and handle. The screws 2 and 2¹ can therefore be turned by turning the driving shaft for screwing up and off the press pots, while with respect to the relative displacement between the 90 screws and the shafts 5 the shortening of the column B, C, B¹, C¹, B², C², during the

pressing is possible. The springs 4 forming a yieldable counter bearing for the screw nuts 3 allows the compensating of differences in the distance between the press pots 5 and their intermediate pieces.

In the second embodiment shown in Figures 3 and 4, in the slide blocks c , c^1 and c^2 will be drawn up against the flanges of the press pieces B^1 , B^2 and against the cross head D , by springs 10, the ends of which act in the same manner as screw nuts, and are screwed on the bearing which is provided with a corresponding outer thread. The lower counter bearings are formed by the journal projections of the slide blocks c , c^1 , c^2 , and the upper bearings by the box shaped journals 11, which are rotatably arranged in the flanges of the intermediate pieces and the cross head. The intensity of the springs can therefore be adjusted. The springs 10 will automatically draw or pull the slide blocks against the intermediate plates and thereby pull the pots against their cover pieces. It may be remarked that it is not necessary that this drawing up or pulling should correspond with the intense pressure utilized during the pressing.

For the purpose of loosening the press pots from the intermediate pieces against the action of the springs 10, the graded pressure rods 12 extend on both sides of the column through the cross head, slide blocks, and the flanges of the pressure heads. These pressure rods 12 press during the downward movement with their projections on the slide blocks. The down-pressing of the rods 12 takes place by the transverse movable bar 13, which is provided with wedge shaped projections 14, which press on the rounded ends of the rod heads. The bar 13, which has an end formed as a screw spindle, can be displaced by the driving shaft 9, as one wheel of the bevel gears 8 forms the spindle nut of the bar 13, which extends through a bearing 15. If the bar 13 is moved back to the right side, the wedge shaped projections 14 are disengaged from the rounded ends of the rod heads 12, and the springs 10 act and in this position, the bar 13 permits the rods 12 a free upward movement through the bores 16. By releasing the press heads from the intermediate pieces by means of the rods 12, the press heads rest on the known graded counter bearings 17.

I have hereinbefore described several embodiments of my invention but do not wish

to be limited in the details thereof since changes may be made therein without departing from the spirit of the invention, as defined in the appended claims.

I claim:

1. A hydraulic press comprising a cross head, press pots, intermediate plates having heads for the press pots, slide blocks for guiding the press pots, shafts disposed through said intermediate plates and the slide blocks, said intermediate plates and slide blocks being movable relatively in a direction axial of the shafts, and resilient means acting between said shafts, intermediate plates and slide blocks and controlled in action by the movement of said shafts.

2. A hydraulic press comprising a cross head, press pots, cover plates for the press pots, hollow screws rotatably mounted in said cover plates and in the cross head, slide blocks for guiding the press pots, nuts in said blocks threaded on said hollow screws, and shafts extending through said hollow screws for rotating the same.

3. In a hydraulic columnar pot press, a crosshead, press pots, flanged intermediate plates with press heads, hollow screws rotatably arranged in the flanges of the intermediate plates, and in the crosshead, slide blocks for the press pots for guiding the same, co-operating female threads for said hollow screws in the slide blocks, shafts arranged parallel with the column of the pots passing through said screws, means preventing rotation between the shafts and hollow screws but permitting displacement in respect to each other, and means for rotating the shafts.

4. In a hydraulic columnar pot press, a crosshead, press pots, flanged intermediate plates with press heads, hollow screws rotatably arranged in the flanges of the intermediate plates, and in the crosshead, slide blocks for the press pots for guiding the same, co-operating female threads, and nuts with spring counter bearings for said screws in said slide blocks, shafts arranged parallel with the column of the pots passing through said screws, and means preventing rotation between the shafts and hollow screws but permitting displacement in respect to each other, and means for rotating the shafts.

In testimony that I claim the foregoing as my invention, I have signed my name hereto.

PAUL HÄNEL.
